UNITED STATES PATENT OFFICE

MAX MARSACK, OF SHEBOYGAN, WISCONSIN

MATTRESS CONSTRUCTION

Application filed November 5, 1928. Serial No. 317,321.

My invention relates to mattresses and particularly to a mattress construction in which there is employed an inner spring construction. The invention has among its objects the production of a mattress of the kind described which is comfortable, durable, attractive in appearance, efficient and satisfactory. The same has particularly among its objects an improved mattress construction whereby the mattress will retain its original shape and attractive appearance after continued use without in any way impairing its comfort qualities. It has as a further object the production of an improved mattress provided with an inner spring construction in which there is unrestricted full play and action of the springs. It has as a further object the production of a mattress provided with a quilted side boxing, the mattress being so constructed that flexing and buckling of the side boxing is slight when the mattress is occupied, and in which the boxing is retrieved and remains substantially taut with the total elimination of buckling when the mattress is not occupied.

Many other objects and advantages of the construction herein shown and described will be obvious to those skilled in the art from the disclosure herein given.

To this end my invention consists in the novel construction, arrangement and combination of parts herein shown and described, and more particularly pointed out in the claim.

In the drawing, wherein like reference characters indicate like or corresponding parts:

Fig. 1 is a top elevation of a portion of a mattress;

Fig. 2 is a side elevation of the same;

Fig. 3 is a sectional view taken substantially on line 3—3 of Fig. 1;

Fig. 4 is a sectional view of a modification;

Fig. 5 is a sectional view taken substantially on line 5—5 of Fig. 2;

Fig. 6 is a view in elevation of a portion of the flap 9; and

Fig. 7 is a view in elevation of a modified form of the flap 9.

Referring to the drawing, in which only two embodiments of the invention are shown, an inner spring construction is illustrated consisting of the desired number of springs 1 arranged in a covering 2, it being understood, however, that any suitable spring construction desired may be employed for the purpose. Over the opposite faces of the spring construction are arranged fillings 3 and covering sheets 4 of ticking or the like, the same being of a size so that its edges extend beyond the edges of the spring construction. About the edge of the mattress between the cover sheets 4 is arranged an edge boxing which consists of the inner ply 5, outer ply 6 and filling 7, the boxing being quilted by means of eyelets 8 or the like securing the inner and outer plies and filling together, so that the same is of substantial body. The edges of the inner ply 5 are secured to flaps 9 which are secured or sewed to the coverings 4 as indicated at 10. It is preferred to make the flaps 9 with the cut-out portions 11 so that the same is more or less scalloped, the portions 12 being secured to the edges of the inner ply. The filling can thus extend through so that it is continuous.

The edge portions 13 of the cover sheets 4 are secured to the edge portions 14 of the outer ply by stitching or binding the same at their juncture 15. Stitches 16 extending through the filling and the adjacent edge portions 13 and 14 form edge rolls 17 extending about the mattress. The mattress may be tufted as indicated at 18 by means of cords or ties extending through the same.

In the construction illustrated in Fig. 4, 20 shows the spring in the spring construction provided with the covering or boxing 21. On the opposed faces of the spring construction is arranged the filling 23 and over this the cover sheets 24. The side boxing consists of the inner ply 25, outer ply 26, and filling 27, the inner and outer plies and filling being secured or quilted together by the eyelets 28 or the equivalent. In this modified construction the cover sheets 24 are secured directly to the spring cover or boxing 21 through the flaps 29 corresponding to the

flaps 9 shown in Fig. 3. These are sewed or stitched to the covering as indicated at 30 and to the spring construction cover as indicated at 31. The edges of the cover sheet 5 and the edges of the outer ply 26 are stitched or bound together at their juncture as indicated at 33, the roll edge stitches 34 extending through the outer ply cover sheet and filling forming the roll edges. It is preferred 10 that the stitches 34 be extended through the edges 35 of the inner ply 25 of the side boxing, thereby preventing of the same from wrinkling down and at the same time it retains the boxing in order. The usual tufting 15 38 or the equivalent may be employed.

In the construction shown it may be noted that the flap 9 forms substantially a plurality of straps. Obviously individual straps may be formed, for example, as indicated in Fig. 7 20 where straps 12' are shown as fastened to the flap 9'. The flap 9' corresponds to the flap 9 without the scallops. The straps 12' may be fastened to the flap 9' by stitching and, if desired, may be alternately fastened 25 on opposite faces of the flap, as shown, or they may all be positioned on one side of the flap. Obviously with either of these constructions when the mattress is occupied the 30 tendency of the load on the mattress is to maintain the side boxing without buckling, there being a pull or tension on the same. The eyelets serve as vents through which air

may pass in or out of the mattress. These eyelets may be arranged in any suitable design so that they not only have utility but may also be used for purposes of ornamentation.

Having thus described my invention it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

A mattress or the like, including; a box-like spring construction including a plurality of vertically arranged coil springs; a layer of cover padding on the top of the spring construction; a cover sheet over said padding carrying an auxiliary strip attached by one edge adjacent the edge of the cover sheet, said cover sheet having its edge attached to the edge of the box-like spring construction; side padding at the sides of the box-like spring construction extending upwardly into the space between the edge of the cover sheet and the auxiliary strip; and a side wall sheet over the side padding, the edge of the side wall sheet being attached to the free edge of the auxiliary strip.

MAX MARSACK.
